(57) **CLAIM**

The ornamental design for a suspended water fishtank, as shown and described.

DESCRIPTION

FIG. 1 is a top perspective view of a suspended water fishtank, showing my new design;

FIG. 2 is a top perspective view thereof, illustrated without fish and water for clarity of illustration;

FIG. 3 is a bottom perspective view thereof;

FIG. 4 is a front elevational view thereof, the rear elevational view being a mirror image thereof;

FIG. 5 is a left-side elevational view thereof, the right-side elevational view being a mirror image thereof;

FIG. 6 is a top plan view thereof; and,

FIG. 7 is a bottom plan view thereof.

The broken lines showing water and fish in FIG. 1 depict environmental matter that forms no part of the claimed design.

1 Claim, 6 Drawing Sheets
